FRED R. TAISEY, OF LOWELL, MASSACHUSETTS, ASSIGNOR TO THE LAMSON COMPANY, OF BOSTON, MASSACHUSETTS, A CORPORATION OF NEW JERSEY.

CABLE-CARRIER SYSTEM.

1,157,192.

Specification of Letters Patent. Patented Oct. 19, 1915.

Original application filed July 17, 1913, Serial No. 779,449. Divided and this application filed January 8, 1914. Serial No. 810,980.

To all whom it may concern:

Be it known that I, FRED R. TAISEY, a citizen of the United States, residing at Lowell, in the county of Middlesex and State of Massachusetts, have invented certain new and useful Improvements in Cable-Carrier Systems, of which the following is a specification.

This invention relates to apparatus, disposed at stations of a cable carrier system, for despatching and receiving carriers, and is particularly adapted to what are known as high-line drop stations in systems of this character. Features thereof may also be employed to advantage in low-line systems.

The present application is a division of my application entitled—Cable carrier system, Serial Number 779,449, filed July 17, 1913, and relates more particularly to certain features of construction and combinations of elements which were shown by way of exemplification in my said former or parent application, but which were not claimed therein.

One of the objects of the present invention is to provide an improved means for elevating a carrier from a station or point disposed at a relatively low level, to a track at a higher level and then to automatically connect the carrier to the propelling cable or otherwise subject it to a propulsive effort of the cable.

Another object of my invention is to provide a novel carrier-hoisting mechanism which is set into operation by a downward push upon the carrier itself after the latter has been inserted in said mechanism.

I have further aimed to provide an improved means whereby this hoisting mechanism may be intermittently operated, as needed, by power derived from the cable or like means which propels the carriers along the main track.

Still another object of the invention is to provide an improved means for operatively engaging carriers with the propelling means.

An important feature of the present construction involves the provision of a tractor or carriage which is adapted to be propelled by the cable which propels carriers along the main track and which is adapted to thereby draw or pull carriers along an auxiliary track leading into said main track.

These and other objects of my invention will be hereinafter referred to and the novel elements and combination of elements whereby they may be attained will be particularly pointed out in the claims appended hereto.

In the drawing I have exemplified a form of the apparatus in question, but I am aware that various changes and modifications may be made herein without departing from the spirit of my invention, and I hence desire to be limited only by the scope of said claims broadly considered in the light of my disclosure.

Referring to the drawing: Figure 1 is a front elevation of a high-line drop station. Fig. 2 is a section of the apparatus shown in Fig. 1; the section being taken on line II—II of said figure. Fig. 3 is a detail section taken on line III—III of Fig. 1. Fig. 4 is a detail front elevation of the carrier or tractor shown in Fig. 1.

The main track in the present instance comprises an upper or incoming track 1 preferably adapted to support carriers horizontally; both portions of the track being disposed in a horizontal plane in a known manner. The lower or outgoing track in the apparatus exemplified has the rails 2—2 thereof disposed in the same vertical plane, but I do not wish to be limited in any way to such disposition of the rails where the claims do not clearly specify such an arrangement.

The main tracks have been respectively designated forwarding and return tracks with respect to the drop or clerk's station 90 and not with respect to the cashier's station. A track comprising rails 3—3 extends up vertically from a point convenient to the operative and is adapted to deliver carriers to a track, the rails of which have been 95 designated 2 (and which may hence for brevity conveniently be referred to as track 2), when the switch or bridge 4 is in its elevated position, indicated by dotted lines at 4' in Fig. 1. A cable 5 serves to propel 100 carriers in the direction indicated by the arrows adjacent thereto, along the respective main tracks, and this cable, it will be noted, is normally substantially free from kinks and bends where passing a station of the 105 character in question, a feature of consid-

erable importance. An independent drop track 6—6 is adapted to receive carriers from a switch 7 to which selective carriers are delivered in a known manner from the upper or horizontal track 1. The respective track sections and switch are suitably connected together and supported by brackets or connections 8, 9, 10, 11, 12, 13 and 14; the switch 4 being mounted upon a shaft 15 journaled in the bracket 9 and most of the remaining brackets serving further to support operating cams, or the like, in the manner hereinafter described.

In the construction herein described the carrier being despatched, is preferably given the right of way and is drawn up from the station by a hoisting cord 16 which is connected at its lower extremity to a pusher 17, which may be of fiber or other suitable material and which is adapted for engagement with the track 3 up and down which it moves.

The cord 16 passes upwardly from its point of attachment 18 to the pusher 17, around an idler 19 mounted upon the bracket 13, and thence around an idler 20 carried by bracket 12; being finally looped around a pulley 21 mounted upon a carriage or tractor 22; the upper extremity of cord 16 being connected to a tension spring 23 which is in turn fastened to the bracket 9. The traveling block or carriage 22 rides upon auxiliary tracks or guides 24, as best shown in Figs. 2 and 3.

The weight of the pusher is normally sufficient to return the carriage to the position in which it is shown in Fig. 1, when displaced therefrom by the cable 5 and after being released from said cable in the manner hereinafter described, and a bumper 25, provided with a compression spring 26, cushions the return of this carriage to its normal position; the outward movement of the spring 26 being limited by a collar 26' on the bumper rod, which collar engages an extension 12' of the bracket 12; the bumper rod being slidably mounted in bracket 9 and having its rear end pivotally connected to an arm 27' keyed to the shaft 15. The rear end of spring 26 bears against an extension 9' of the bracket 9.

The carriage 22 carries upon one side thereof a fixed jaw 27 and has pivotally mounted in operative relationship to this jaw a grip element or jaw 28 against the flattened hub of which, within the carriage, a spring 29 bears in such a manner as to hold the pivoted jaw in its open as well as in its cable gripping position, when moved into either of these positions; this spring further having a tendency to snap the jaw 28 closed when it has been swung inwardly part way by the cam 30, which occurs when the carriage is retracted against the action of buffer spring 26 by a downward thrust upon

the pusher 17, by means of the carrier being despatched. The jaw 28 while pivoted preferably interiorly of the carriage extends out therefrom through a slot 28' in a manner common to cable carrier construction. 70

The grip mechanism comprising jaws 27 and 28 is in fact practically a duplicate of that provided upon each of the carriers and is intended to operate in substantially the same manner. A description of the construction of the carriers need not be herein given, since they are practically identical with the carrier shown in the patent to George A. Amsden #960,617, dated June 7, 1910. It may also be here noted that spring 26 is sufficiently strong to resist the pull exercised upon the cord 16 by the descending unloaded pusher after the despatch of a carrier, so that the cam 30 cannot inadvertently reengage the carriage with the 85 cable 5.

The guides 24, as shown in Fig. 2, are spaced for the greater part of their length a sufficient distance from the cable 5 to prevent the jaws of the carriage 22 becoming inadvertently engaged with the cable and also to insure proper clearance for the carriers traversing track 2. These guides, however, are inwardly directed toward said cable at their inner ends, as shown in Fig. 3, so that 90 when the carriage is retracted against the action of spring 26, the jaws 27 and 28 are brought into position where they may be caused by cam 30 to grip the cable; while the bracket 8 carries a cam 31 which is adapted to 100 swing open the pivoted jaw 28 when the carriage has moved to substantially the forward limit of its travel. The hub of the bridge 4 is notched, as at 32, for engagement with the toe of a latch 33, which is pivotally mounted 105 at 34 upon another extension of the bracket 9; said latch being normally held in its operative position by means of a spring 33' attached to the bracket 13 and to an arm 35' of said latch. The latch is also provided with a lug 36 which is adapted for engagement with a cam acting hook 37 mounted upon the pusher 17.

An arm connected to the switch or bridge 4 has pivotally connected to the upper side 115 thereof at 38 a link 39 which extends in parallelism with the track 2, at this point, and is connected at 40 to an arm of a bell-crank or bent lever 41; the link 39 also being connected at a suitable intermediate point 120 42 to the corresponding arm of the crank shaped element 43. The element 41 has its free end 41' shaped for engagement with the pivoted jaw of carriers traversing track 2; said jaw, as above stated, being substantially 125 like the jaw 28 of the carriage 22 and also like the pivoted jaw of the carrier shown in the patent to Amsden above referred to. In fact when the element 41 is disposed in its dotted line position it behaves like the com- 130

monly provided fixed grip opening cams in use in cable carrier systems, but unlike these fixed cams it is adapted to be swung downwardly out of possibility of engagement with the pivoted grip member of a passing carrier. Correspondingly the free end 43' of the element 43 is adapted to engage and open the pivoted jaw of the grip of carriers traversing track 2 which may have succeeded 5 in passing the movable cam 41' without having their grips opened, as for example, when the switch is open and the elements 41 and 43 are thereby moved into their operative positions while a carrier is between said 10 elements. The element 43 is not only adapted to open the grip of a carrier but furthermore serves as a stop for said carrier or for a carrier whose grip has been opened by the cam 41. A fixed grip opening cam 44 is 15 mounted upon the bracket 13 in the path of a carrier ascending from the station, for the purpose of opening the cable grip of the carrier 45 when the latter has been inserted through the usual aperture 46 of the track 3, 20 with its grip closed. It will be understood of course that the aperture 46 is adapted for the reception of the lugs 45' commonly provided upon the carriers of this description for the purpose of retaining them upon the 25 track along which they ride.

For convenience and simplicity of construction the inner rail of the track 3 is cut away upon its sides as at 47 so that it may be received into a slot 48 in the free end 30 of the switch or bridge 4 when the bridge is in the position in which it is shown in full lines in Fig. 1. This reduced portion 47 of the inner rail 3 quite closely engages the bifurcated end of the bridge and holds 35 the latter firmly against lateral displacement in the horizontal plane, when said bridge is down; and the corresponding cut away portion 47' of the upper rail of track 2 correspondingly enters said slot 48 when the 40 bridge is in its closed position. Finally, it will of course be understood that the bridge or at least that portion thereof which is engaged by a carrier ascending from the station, is of substantially the same thickness 45 as the track 3.

The operation of the construction above described will, in view of the foregoing, be at once apparent. The carrier 45 is inserted at 46 and pressed downwardly against the 50 pusher 17 which draws the carrier-like device or carriage 22 rearwardly and also causes it to approach the cable 5 until its jaws are operatively engaged with the latter by the cam 30, which rocks the pivoted jaw 28 up until it engages or practically engages cable 5, whereupon both spring 29 and the cable act to swing it into operative position; the cable drawing the carriage along with it, and thereby pulling up the pusher and the 55 carrier supported thereby until the carrier

passes a considerable portion at least of the bridge 4 and has acquired sufficient momentum to insure its being ejected onto main track 2. When the carriage 22 was thus drawn rearwardly it was strongly pressed 70 against the bumper 25 which drove back the bumper rod, within spring 26, and thereby rocked the arm 27' rearwardly. This in turn rotated the shaft 15 clockwise, as viewed in Fig. 1, and lifted the bridge 4 to 75 its dotted line position in which it was then held by latch 33. Simultaneously with this upward movement of the bridge, the link 39 is driven rearwardly by reason of its connection with the bridge, which disposes the 80 carrier grip-tripping and stopping members 41 and 43 in position to check the progress of a carrier approaching the station and *en route* along track 2. The link 39 in the present instance is merely a straight bar, but it is 85 adapted when raised, as it is by a forward movement thereof caused by the return of the bridge to its normal position, to engage the pivoted grip element of any carrier or carriers which may be disposed thereabove 90 and by forcing said element or elements upwardly toward the cable 5, to thereby re-despatch said carrier or carriers. The bridge 4 is locked in its upper position by the latch 33, but when the pusher 17 has 95 been drawn up sufficiently to permit its cam hook 37 to engage the lug 36 of said latch, the latch is moved to its open position and the bridge released. As previously stated, this causes a slight elevation of the link 39 100 together with a forward movement thereof and simultaneously lowers the cams or trips 41' and 43'.

The release of the bridge occurs shortly before the carriage 22 reaches the limit of its outward travel, so that the spring 23 is 105 slightly stretched. The instant after the bridge is unlatched, however, the grip opening cam 31 in the path of the jaw 28, swings the latter down; freeing the carriage from 110 the cable and permitting it to be returned to its normal position; the cable having been pulled laterally out of its normal path by the carriage jaws and hence tending to immediately emerge from between these jaws 115 when the latter are opened. The return of the carriage to its normal position by the weight of the pusher 17 is preferably relatively slow as compared to the speed of the cable, the carriage moving back but half as fast as the pusher descends, and hence the impact of the carriage against its bumper is insufficient to effect an inadvertent re-elevation of the bridge through the connection of the bumper with the latter; even though 120 the bridge be relatively light in weight. Further, the looping of the flexible element or hoisting cord 16, around pulley 21, permits the despatch of a carrier along track 3 at a speed materially greater than the de- 125 130

terminated or normal speed at which said carrier is afterward drawn along track 2 by the cable. When the pusher is driven down as by the pressure of the hand of the operative against the carrier to be despatched, it may happen that if the hoisting cord has not been properly adjusted, for length, the tractor may become engaged with the cable before the bridge has been quite elevated to its latching position; but even this will not materially affect the operation of the apparatus since in such case the bridge will be lifted or opened by the ascending carrier itself, which action will of course elevate the grip-tripping elements 41' and 43' as before. Indeed, even should the latch become wholly ineffective, the bridge would not only be operatively displaced by the carrier being despatched but would further be held open by said carrier until the latter had cleared it, and the trips 41' and 43' would be effectively disposed to check the progress of a through carrier, in the manner above described, until the bridge was allowed to close by the emergence of the carrier being despatched from the station, from beneath said bridge. Thus the apparatus is but little subject to disarrangement and provides a dependable and efficient mechanism for the despatch of carriers from a cable drop-station. It will be observed, also, that while one side of the cam 30 serves to close the carriage jaw 28, as above described, the other side of this cam serves to close upon the cable; the corresponding jaw of the carrier being despatched, so that this member performs a double function.

The provision of a reciprocable traction carriage provided with a cable-gripping means together with devices for engaging and disengaging such means respectively with and from the cable, in devices of this description is believed to be very broadly new. I am aware, however, that other means for effecting reciprocation or to and fro movement of such a device may be used in lieu of the cable and a weight (pusher 17) or its equivalent, and hence do not desire to be limited to a cable propelled tractor of this description except when the claims specifically so indicate. I also desire to call particular attention to the provision of the movable means, *e.g.*, cams, trips or the like, such as the parts 39, 41' and 43' for arresting determined carriers under certain conditions and for effecting their reengagement with or re-subjection to the influence of the cable or other propelling means.

In the apparatus given by way of exemplification were it not for the provision of at least one of the cams or trips 41' and 43', or some equivalent thereof, a carrier *en route* past the station would encounter the bridge 4 when the latter is raised which, if 65 the grip of the carrier were not open under

such condition, would result in "burning" or otherwise injuring the cable or other parts.

The advantage of providing a plurality of grip opening cams or parts 41' and 43' resides in the fact that if, for example, two carriers, relatively close together are *en route* along track 2 past the station, and a carrier is being despatched from said station which would collide with the bridge, the first carrier will either have its grip opened by cam 41' and be stopped by cam 43', or it will have its grip opened by cam 43' and will also be stopped by said cam, and the grip of the succeeding carrier will be opened by cam 41' so that while it comes to rest against the first carrier neither of these carriers will have their grips operatively engaged with the cable at such time. This permits, in effect, of a temporary storage of a plurality of carriers above the link 39.

The provision of means, *e.g.*, the switch 7 and track 6, for receiving carriers from the return track which are substantially independent of the power driven carrier delivering mechanism, is of special value in a system of the character described, since it permits of the despatch of carriers from the station by said mechanism without interference therewith by carriers arriving at the station. It will be noted, too, that the track or way leading from the station to the forwarding track is of substantially the same gage as said forwarding track; the carrier being successively directed into engagement with and positively propelled along both of said tracks.

The provision of the spring 23 in connection with the hoisting cord eliminates the necessity for any very nice adjustment of parts and further serves to impart an initial return impulse to the carriage or tractor after it has been freed from the cable by the cam 31.

It will be understood of course, that while the tractor carriage is, in the present instance, provided with bifurcated lugs at the respective extremities thereof which serve to maintain it in engagement with the respective parts of its guide-way; other means may be employed to maintain it in position thereon. Further, when in certain of the appended claims I have broadly characterized this carriage as a "device", I desire it to be understood that this term is of sufficient breadth to cover any construction to which it may properly be applied in view of my disclosure; attention being particularly directed in this connection to the similarity of the carriage shown by way of exemplification to the preferred type of carrier.

Having thus described my invention what I claim is:—

1. Cable carrier apparatus comprising a 130

main track, an auxiliary track, a carrier to travel along said track, a continuously driven cable adjacent said main track, a tractor having means for engaging said cable, means whereby said tractor may propel said carrier along said auxiliary track toward said main track, and automatic means for engaging said tractor with said cable.

2. Cable carrier apparatus comprising a main track, an auxiliary track, a carrier to travel along said track, a continuously driven cable adjacent said main track, a tractor having means for engaging said cable, means whereby said tractor may propel said carrier along said auxiliary track toward said main track, and automatic means for disengaging said tractor from said cable.

3. Cable carrier apparatus comprising a main track, an auxiliary track, a carrier to travel along said track, a continuously driven cable adjacent said main track, a tractor having means for engaging said cable, means whereby said tractor may propel said carrier along said auxiliary track toward said main track, and automatic means for engaging said tractor with said cable and for disengaging it therefrom, thereafter.

30 4. Cable carrier apparatus comprising a track, a guideway in substantial parallelism therewith, a carrier adapted to travel on said track, a tractor to travel on said guideway, a cable to propel said carrier along said track, means to connect said tractor with said cable, and means whereby said tractor may operatively position said carrier with respect to said cable.

5. Cable carrier apparatus comprising a way, a carrier adapted to travel along said way, a power driven cable, a carriage having means to engage said cable, means to propel said carrier along said way by a movement of said carriage, and means to automatically disconnect said carriage and cable.

6. Cable carrier apparatus comprising a way, a carrier adapted to travel along said way, a power driven cable, a carriage having means to engage said cable, means to propel said carrier along said way by a movement of said carriage, and means to automatically disconnect said carriage and cable after said carrier has been propelled a determined distance by said carriage.

55 7. Carrier apparatus comprising a way, a carrier to travel thereon, said way having provisions for permitting the emplacement of said carrier in direct operative engagement with said way, power means normally moving in a determined direction, means adapted to be propelled by said power means to propel said carrier along said way, means to subject said carrier propelling means to the action of said power means, and means to free said propelling means from such

action and to subject said carrier to the direct action of said power means.

8. Cable carrier apparatus comprising a continuously driven cable, a carriage having means to engage said cable, a way, a carrier, means to propel said carrier along said way by a movement of said carriage, and means to automatically free said carriage from said cable and to directly connect said carrier to said cable.

9. Cable carrier apparatus comprising a main track, a branch track, a flexible element to propel carriers along said main track, an auxiliary element to propel carriers along said branch track and means to automatically connect and disconnect said elements.

10. Cable carrier apparatus comprising a main track, a branch track, a flexible element to propel carriers along said main track, an auxiliary element to propel carriers along said branch track, means to connect and disconnect said elements, said carriers having means adapted to engage said flexible element and a part of said first mentioned means also being adapted to actuate said last mentioned means to effect its said engagement with said flexible element.

11. Cable carrier apparatus comprising a track, a carrier to travel along said track, means, including a reciprocable tractor for emplacing said carrier on said track at a determined point in the latter, and means, actuated by power transmitted through said tractor, for checking the progress of a carrier traveling along said track toward said point when said first mentioned carrier is being delivered to said track by said tractor.

12. Carrier despatch apparatus comprising a track, a carrier to travel along said track, and means, including a reciprocable tractor adapted to travel in substantial parallelism with said track, for emplacing said carrier on said track.

13. Cable carrier apparatus comprising a main track, a branch track of substantially the same gage as said main track, carriers to travel along said tracks, means, including a reciprocable tractor, for propelling a carrier along said branch track toward said main track, a cable for propelling a carrier along said main track, and collision preventing means for checking the progress of a carrier on one of said tracks, said means being adapted to be rendered operative by power derived from said cable.

14. Cable carrier apparatus comprising a main track, a branch track of substantially the same gage as said main track, carriers to travel along said tracks, means, including a reciprocable tractor, for propelling a carrier along said branch track toward said main track, a cable for propelling a carrier along said main track, and collision prevent-

ing means for checking the progress of a carrier on one of said tracks when a carrier is traversing the other of said tracks toward and past a determined point in said last 5 mentioned track.

15. Cable carrier apparatus comprising a guide-way, a propelling cable to travel in a determined direction, a device to travel on said guide-way and having means to engage 10 said cable, and means to connect said cable engaging means with said cable by a movement of said device in a direction substantially opposite to the determined direction aforesaid.

16. Cable carrier apparatus comprising a guide-way, a propelling cable to travel in a determined direction, a device to travel on said guide-way and having means to engage 20 said cable, means to connect said cable engaging means with said cable by a movement of said device in a direction substantially opposite to the determined direction aforesaid, and means to move said device in said opposite direction.

25. 17. Cable carrier apparatus comprising a guide-way, a propelling cable to travel in a determined direction, a device to travel on said guide-way and having means to engage said cable, and means to connect said cable 30 engaging means with said cable by a movement of said device in a direction substantially opposite to the determined direction aforesaid, said cable and cable engaging means being disposed with respect to each 35 other, prior to said movement in said opposite direction, to prevent inadvertent operative engagement therebetween.

18. Cable carrier apparatus comprising a guide-way, a propelling cable to travel 40 in a determined direction, a device to travel on said guide-way and having means to engage said cable, means to connect said cable and cable engaging means, means to thereafter disconnect said cable engaging means 45 from said cable, and means to move said device along said guide-way in a direction opposite to that in which it travels when propelled by said cable.

50. 19. Cable carrier apparatus comprising a guide-way, a propelling cable to travel in a determined direction, a device to travel on said guide-way and having means to engage said cable, means to connect said cable and cable engaging means when said 55 device is moved in a direction substantially opposite that in which it is moved by said cable when connected thereto, means to thereafter automatically disconnect said device from said cable, means to return said 60 device toward said second mentioned means, and means to prevent inadvertent re-connection of said device with said cable upon the said return.

65. 20. Cable carrier apparatus comprising a guide-way, a propelling cable to travel in

a determined direction, a device to travel on said guide-way having a pulley attached thereto, a flexible connection in engagement with said pulley, a carrier, means to propel said carrier by a movement of said flexible connection, and means to connect said device with said cable. 70

21. Cable carrier apparatus comprising a guide-way, a device to travel thereon, means to automatically reciprocably move said device along said guide-way, said means including a power driven cable and means to connect and disconnect said device and cable. 75

22. Cable carrier apparatus comprising a guide-way, a device to travel thereon, means to automatically reciprocably move said device along said guide-way, said means including a power driven cable and means to connect and disconnect said device and cable, 80 and a bumper for limiting the movement of said device when traveling in one direction.

23. Cable carrier apparatus comprising a guide-way, a device to travel thereon, means to automatically reciprocably move said device along said guide-way, said means including a power driven cable and means to connect and disconnect said device and cable, 85 and a bumper for limiting the movement of said device when traveling in one direction, said bumper adapted to normally prevent further reciprocation of said device after the latter has impinged thereagainst. 90

24. Cable carrier apparatus comprising a guide-way, a device to travel thereon, flexible means to propel said device in one direction along said guide-way, means to connect and disconnect said device and flexible means, and means to retract said device after it has been propelled by said flexible 100 means. 105

25. Cable carrier apparatus comprising a guide-way, a device to travel thereon, a cable to propel said device in one direction and separate means to retract said device after it has been propelled by said cable. 110

26. Cable carrier apparatus comprising a guide-way, a device to travel thereon, a cable to propel said device in one direction and yielding means to retract said device after it has been propelled by said cable. 115

27. Cable carrier apparatus comprising two substantially independent guide-ways, a device to travel on one of said guide-ways, a second device to travel on the other of said guide-ways, a cable to propel the first of said devices, and connections to propel the second of said devices by a movement of the first by its said cable. 120

28. Cable carrier apparatus comprising two substantially independent guide-ways, a device to travel on one of said guide-ways, a second device to travel on the other of said guide-ways, a cable to propel the first of said devices, connections to propel the sec- 125 130

ond of said devices by a movement of the first by its said cable, both of said devices having means to engage said cable, and said apparatus further comprising means to disconnect the first of said devices from said cable before said second device is engaged with said cable.

29. Cable carrier apparatus comprising, a cable, two guide-ways, a device to travel on one of said guide-ways, a second device to travel on the other of said guide-ways, each of said devices having means to engage said cable and to be propelled thereby along its respective guide-way, and means to normally disengage one of said devices from said cable as it reaches a determined point in its guide-way, when the other of said devices is operatively connected to said cable.

30. Cable carrier apparatus comprising a track, a carrier to travel on said track, a propelling cable normally driven at a determined speed, and means to propel said carrier, by power derived from said cable, at a speed materially in excess of that of said cable.

31. Cable carrier apparatus comprising a track, a carrier to travel on said track, a propelling cable normally driven at a deter-

mined speed, and means to propel said carrier, by power derived from said cable at a speed substantially twice as fast as that of said cable.

32. Cable carrier apparatus comprising a main track, a reciprocably mounted tractor, a cable, means for connecting and disconnecting said tractor with and from said cable, an auxiliary track, a switch at the point of delivery of said auxiliary track to said main track, and means for actuating said switch by a movement of said tractor.

33. Cable carrier apparatus comprising a main track, an auxiliary track leading thereto, a cable to propel carriers along said main track, a device movable by said cable in one direction, means to move said device in an opposite direction, a switch at the junction of said tracks, and means to move said switch in accordance with a movement of said device.

In testimony whereof I have affixed my signature, in the presence of two witnesses.

FRED R. TAISEY.
